UNITED STATES PATENT OFFICE.

RAPHAEL A. PORTA, OF NEW YORK, N. Y.

APPARATUS AND METHOD OF PERMANENT HAIR WAVING.

Application filed March 21, 1927. Serial No. 177,103.

This invention relates to an apparatus and method of permanent hair waving and has for an object to provide an improved construction of squeezing member for limiting the amount of moisture used on each section of hair.

Another object is to provide an improved method of treating hair wherein all parts of the hair are subjected to substantially the same amount of moisture as well as the same amount of heat.

A still further object is to provide an improved method of permanent hair waving, wherein the moisture and chemical treating members are quickly put in place by a sliding action instead of a winding action.

In the accompanying drawing—

Figure 1 is a fragmentary view of a head showing two sections of hair with a sachet roll being applied to one section of hair.

Figure 2 is a top plan view of a pair of squeezing pliers embodying certain features of the invention.

Figure 3 is a sectional view through Figure 2 on line 3—3.

Figure 4 is a perspective view of the operating end of the pliers shown in Figure 2, the same being shown open.

Figure 5 is a perspective view of a sachet roll, embodying certain features of the invention.

In the art of permanent hair waving, the hair must be wound on rolls or suitable supports of some kind preparatory to applying the chemicals and heat. Sometimes there may be, for instance, twenty-eight of these sections or rolls and sometimes as high as forty. Heretofore, after the sections or rolls have been made, a moistened pad carrying chemicals, known as a sachet pad, is wound around each section or roll of hair and fastened in place so that little or no vapor can escape from the ends. After this has been done, the heat is applied exteriorly of the sachet pad whereby the moisture will be converted into vapor and cause the chemicals to act on the hair while the air is heated, thus setting the same into a permanent wave or condition. Where there is a large number of these sections or coils of hair to be treated, it has been found that some of the first sachet pads to be applied will be almost dry when the last are placed in position. When this happens and the same amount of heat is applied to all coils of

hair, the resulting work will not be entirely satisfactory. No efficient means has been provided for regulating the amount of moisture applied to each pad nor has there been provided any means whereby the pads may be put on quickly so that little or no moisture will have evaporated before the heat is applied. In the present invention, means have been provided for regulating the amount of moisture on each pad and in addition, pads have been reconstructed to tubular form whereby they may be quickly placed in position.

Referring to the accompanying drawing by numerals, 1 indicates a head with two sections or bunches of hair 2 and 3 extending therefrom, said bunches of hair being wound into coils or sections 4 on the respective rods or pins 5 and 6. These rods or pins are metal and are of usual construction now in common use. As indicated in the bottom of Figure 1, the sachet roll 7 is loosely slid in place over the section 4. After it has been placed in position on section 4, the ends are clamped down or tied in any desired manner, said clamping action being of the usual kind now in common use which usually involves a metal clamp with pads for preventing any accidental leakage of moisture to a position in contact with the scalp.

The pads 7 are made in the same way that the pads heretofore have been made, as far as the material is concerned, but are formed into tubes instead of being flat, whereby they may be slid into position instead of rolled and then tied. It has been the custom heretofore, to use the flat pads and to dip them in water or other liquid immediately before rolling the same on the hair. After dipping in the liquid, the pads heretofore were pressed by the hand for squeezing out some of the excess moisture. In the present invention, the pad 7, which is tubular, is dipped in water or other liquid in the same manner as heretofore, but as this pad is tubular in form, it cannot be squeezed by the hand and, consequently, an improved squeezer 8 is provided which is formed to squeeze out a certain amount of moisture whereby all the pads will have the same amount of moisture when applied. As the pads may be quickly dipped, squeezed and applied, it will only take a very few minutes to apply all the pads necessary and, consequently, in view of this quick action,

substantially none of the moisture will have escaped so that the application of heat will cause a uniform action on the hair and, consequently, the result is highly satisfactory.

- 5   The squeezer 8 is provided with handle members 9 and 10 pivotally connected together by a pin 11, which pin is provided with an extension 12 having a right angle portion 13 merging into a tubular member 14. The tubular member or core 14 is adapted to receive one of the tubular pads 7 while in the position shown in Figure 4 and then the squeezing plates 15 and 16 are brought over so that the parts will assume the position shown in Figure 3. The parts are so proportioned that when the edges 17 and 18 meet, a certain definite squeezing action will be produced. As all of the pads 7 are of the same size, this 10 squeezing action is always the same. The pads will be placed in position always with the same amount of moisture and, consequently, desirable uniform results will be secured. It will be noted that the core 14 is provided with a rounded end 19 whereby the pad may be readily slipped in position and then squeezed. The plates 15 and 16, are welded or otherwise rigidly secured to arms 20 which are really extensions of the handle 15 members 9 and 10, which handle members are crossed and clamped together by the pin 11.

By the present invention, the method of permanent waving is secured first, by preparing the hair in the usual manner so as to present the coil sections 4. A suitable number of tubes 7 are then secured and quickly dipped in water or other liquid, squeezed by the squeezer 8 and slid into position. Immediately after each pad has been slid into position, the ends are clamped down in the usual manner heretofore well known, though any other form of clamping may be used to substantially close the ends of the tubes 7. After all of the tubes 7 have been placed in position, any suitable or usual form of heating member is placed around the same and the heat turned on for the usual length of time and then the parts

taken off and the treatment is completed as far as making the permanent wave is concerned. This method and the structures for securing the same, cause a quick action after the sections 4 have been built up so that the results are better than by the method heretofore used because of the quickness with which the pads 7 may be placed in position. This quickness results in having the same amount of moisture in each section 4 and this equal amount of moisture in turn results in a uniform action on all of the hair.

What I claim is:

1. An apparatus used in permanent hair waving, comprising a pair of squeezing plates, a holding core, and means for actuating said squeezing plates.
2. A squeezer for permanent waving pads, comprising a foraminous core, a pair of squeezing plates operatively associated with the core, and pivotally mounted means for actuating said squeezing plates.
3. A squeezer, comprising a pair of arc-shaped plates, a pair of pivotally mounted handles for supporting said plates for moving the plates toward and from each other, a foraminous core, and means extending from the core for supporting the core, said means being operatively connected with the pintles of said handles.
4. A squeezer for squeezing tubular pads used in permanent hair waving, comprising a foraminous core for receiving said tubular pads, a pair of squeezing plates positioned to surround said pads and press the same against said core when the plates are closed, means for pivotally connecting said plates together, said means including a pivotal pin having an extension acting as a support for said core, and means for causing said plates to function.

5. In a tube squeezing device, a foraminous core, a pair of arc-shaped squeezing plates, and means for moving said plates toward and from each other in such a manner that when the plates are in contact said core will be positioned centrally thereof.

RAPHAEL A. PORTA.
